UNITED STATES PATENT OFFICE.

WILLIAM P. THORPE, OF SUGARGROVE, PENNSYLVANIA.

MACHINE FOR WASHING MILK-CANS.

1,111,624.

Specification of Letters Patent. Patented Sept. 22, 1914.

Application filed June 1, 1914. Serial No. 842,130.

To all whom it may concern:

Be it known that I, WILLIAM P. THORPE, a citizen of the United States, residing at Sugargrove, in the county of Warren and State of Pennsylvania, have invented certain new and useful Improvements in Machines for Washing Milk-Cans; and I do declare the following to be a full, clear, and exact description of the invention, such as will enable others skilled in the art to which it appertains to make and use the same.

My invention relates to improvements in devices for washing milk cans and the like and has for its primary object to provide a device of this character, having a number of brushes, so constructed as to allow the brushes to be extended when a can is being washed and retracted when not in use. In carrying out the above end, it becomes necessary to force the can against certain of the brushes in order that they may be extended to operative position.

A secondary object of the invention therefore becomes to construct the device in such a manner as to prevent injury to the bristles of the brushes, by this operation.

A further object of the invention is to provide simple means, in connection with the above set forth elements, for thoroughly cleansing the outside of the can, it being understood that the previously set forth structure is designed for washing the inside thereof.

A still further object is to construct the entire device in such a manner as to render the same simple and inexpensive in construction and well adapted to the uses for which it is designed.

With these objects in view, the invention resides in certain novel features of construction and combination herein described and claimed and shown in the drawings wherein:

Figure 1 is a longitudinal section through the washing tank of the machine, showing the position which the various parts assume before a can is placed upon the brushes; Fig. 2 is a similar view showing the position of parts when washing the interior of a can; and Fig. 3 is a transverse section showing more particularly, the position of the actuating means for the brush employed for washing the exterior of the can, and taken on line 3—3 of Fig. 2.

In the accompanying drawings, I have shown a water tank 1 which may be sup-

ported upon suitable legs 2 and which may be of any necessary proportions.

Projecting rotatably through one end wall of the tank 1 is a shaft 3 which may be driven by means of a suitable belt 4, passing around a suitable drive pulley (not shown) and over a pulley 5 on said shaft. As clearly seen in the drawings, suitable bearings 6 are provided for revolubly supporting said shaft 3. The end portion of the shaft 3, located within the tank 1, is provided with a pair of longitudinally spaced collars 7 which are adjustably secured thereon by set screws 8, said collars being provided with laterally projecting ears 9 which project therefrom at diametrically opposite points, said ears forming pivotal supports for the inner ends of links 10, the latter having their outer ends pivoted at 11 to a pair of longitudinal strips 12 which constitute the backs of brushes 13 and have their ends, disposed adjacent the end wall through which the shaft passes, curved inwardly as indicated at 14 in order that the shape of the brushes may conform to the shape of the upright wall W to a milk can C. As most clearly seen in Figs. 1 and 2, coil springs 15 are attached to the shaft 3, between the collars 7 and appropriate portions of the brushes, thereby normally retracting the latter as seen in Fig. 1. When however, the can C is placed in the tank and moved so as to position the brushes 13 in its interior, the ends 16 of the rectilinear portions of the strips 12, being in contact with the bottom B of the can will cause the brushes 13 to move outwardly as the can is forced still farther in the proper direction, this movement being caused by the fact that the links 10 swing around their pivots against the tension of the springs 15. The shaft 3 may now be rotated and the can held firmly thereby thoroughly washing the interior of its upright wall.

In order to adapt the device for the cleaning of the interior of the bottom B, I have provided a third scrubbing brush 17 which is hingedly connected to the inner end of the shaft 3, one side portion of said end being rounded as at 18 for the purpose of allowing the links 20, constituting the hinged connection, to swing to a position transverse of the shaft, thereby allowing the brush 17 to lie substantially in longitudinal alignment with said shaft. It will therefore be

seen that as the strips 12 contact with the bottom B, the free end of the back to the brush 17 likewise contacts therewith, thereby causing the last mentioned brush to swing outwardly to operative position simultaneously with the moving of the brushes 13 but that no direct strain occurs on the active ends of the bristles forming said brush 17. This is an extremely important 10 feature of the invention, since unnecessary mutilation of the bristles is obviated. In most cases I prefer to provide a coil spring 17' attached to the collar 7 at the inner end of the shaft and to the hinged end of the brush 17, for the purpose of swinging said brush to inoperative position.

For the purpose of washing the exterior of the can, I have provided a suitable brush 21 which is carried by a pair of curved arms 22, pivotally connected to one side of the tank 1, said brush normally lying within the tank and out of contact with the can C. When however, it is desired to move said brush into contact with the can, a foot lever 23, pivoted at one end to a suitable supporting bracket carried by the tank 1, may be depressed, this movement raising said brush through the instrumentality of a cable 24 which rises from the lever 23 outside the tank 1, passes over the pulley 25 carried thereby and then depends and is connected to said brush.

From the above set forth operation it will be seen that the can must be held stationarily for the purpose of allowing the brushes 13 and 17 to cleanse its interior but that the can is allowed to rotate with said brushes for the purpose of allowing the brush 21 to wash its exterior.

40 As shown in Figs. 1 and 2, a pair of cushioning springs 15' may be attached to the shaft 3 in any suitable manner as by brazing or soldering to limit the inward movement of the brushes 13 and to assist 45 in projecting the same.

Having thus described my invention, what I claim as new and desire to secure by Letters Patent is:

1. A device of the character described 50 comprising a shaft, a pair of longitudinally spaced links pivoted to one side thereof, a longitudinal brush pivoted to the outer ends of said links and a second brush hingedly connected to one end of said shaft and movable independently of the other brush for the purpose set forth.

2. A device of the character described

comprising a shaft, a pair of longitudinally spaced links pivoted at their inner ends to one side thereof, a longitudinal brush pivoted to the outer ends of said links, a diagonally disposed coil spring attached to said shaft and to the brush, a second brush having its back disposed adjacent one end of the shaft, and hinge links carried by said last mentioned brush and pivoted on opposite sides of the shaft, said first mentioned brush projecting beyond said last mentioned brush when the device is folded by said coil spring, the two brushes being independently 70 movable.

3. In a device of the character described, a water tank, a pair of curved arms pivoted thereto and depending from their pivots, a brush carried by said arms, a pulley on one 75 edge of the tank, a foot lever pivoted beneath the tank and a cable passing from the foot lever to the brush and around the pulley.

4. In a can washing device, a longitudinal 80 driving shaft having its inner end rounded on one edge, a pair of pivot links pivotally connected to said inner end, a transverse brush having its back pivotally connected to the opposite ends of said pivot links adjacent one of its ends, a pair of collars spaced longitudinally upon said shaft, set screws for securing said collars in adjusted position thereon, a coil spring secured at its opposite ends to one of said collars and to 90 the pivoted end of said brush, pivot ears formed on opposite sides of said collars, links pivoted at their inner ends to said ears, longitudinal strips pivotally connected on their inner faces with the outer ends of said 95 links, said strips having one of their ends curved inwardly, bristles projecting outwardly from said strips and the curved ends thereof and coil springs connected at their outer ends to said strips, said springs projecting inwardly and being connected to the shaft adjacent one of the collars, whereby the tension of said springs may be exerted to normally move said strips inwardly, said strips projecting beyond the end of the first 100 mentioned brush when folded.

In testimony whereof I have hereunto set my hand in presence of two subscribing witnesses.

WILLIAM P. THORPE.
